US00D406822S

United States Patent [19]

Huber et al.

[11] Patent Number: Des. 406,822

[45] Date of Patent: **Mar. 16, 1999

[54] **CARRIER ELEMENT FOR A SEMICONDUCTOR CHIP FOR INTEGRATION INTO A CHIPCARD, OR A CHIPCARD MODULE**

[75] Inventors: **Michael Huber**, Nittendorf; **Peter Stampka**, Schwandorf-Klardorf, both of Germany

[73] Assignee: **Siemens Aktiengesellschaft**, Munich, Germany

[**] Term: **14 Years**

[21] Appl. No.: **76,605**

[22] Filed: **Sep. 8, 1997**

[30] **Foreign Application Priority Data**

Mar. 6, 1997 [DE] Germany ..... M 97 02 260.8

[51] LOC (6) Cl. **13-03**

[52] U.S. Cl. **D13/182**

[58] Field of Search D13/182; 361/748, 361/752, 809; 174/250, 253, 255

Attorney, Agent, or Firm—Herbert L. Lerner; Laurence A. Greenberg

[57] **CLAIM**

The ornamental design for a carrier element for a semiconductor chip for integration into a chipcard, or a chipcard module, as shown and described.

DESCRIPTION

The single FIGURE is a top perspective view of a carrier element for a semiconductor chip for integration into a chipcard, or a chipcard module showing our new design. The features on the undisclosed bottom are not claimed.
